FIRE ESCAPE

William H. Yancey, Louisville, Ky.

Application September 13, 1950, Serial No. 184,618

1 Claim. (Cl. 227—34)

The present invention relates to a fire escape of the type employing a stationary lowering unit and a mobile carrier unit, the two units being connected by a rope or cable.

It is an object of the present invention to provide a fire escape of the type described which will safely and rapidly lower one or several escapees secured to the carrier unit of the fire escape.

Another object of the present invention is the provision of a fire escape having a carrier unit for the escapees, the rate of descent of which is under the complete control of the lowering unit and which may be stopped at any point in its descent to pick up additional persons.

Other objects of the invention will be apparent from the following description of the present preferred form of the invention taken in connection with the accompanying drawings, wherein:

Figure 1 is a front elevational view of the present invention as applied to a building, the carrier unit being shown in escape position;

Figure 2 is a vertical sectional view taken along the line 2—2 of Figure 1, looking in the direction of the arrows, and showing the fire escape in elevation;

Figure 3 is a front elevational view of the fire escape per se; and

Figure 4 is a side elevational view of the carrier unit forming a part of the present invention.

Referring now in greater detail to the drawings, I have, in Figures 1 and 2, shown the fire escape of the present invention in operative position in a building 9. The fire escape comprises generally, a lowering unit A and a carrier unit B, the latter being shown outside a window 10 of the building 9.

Lowering unit A embodies a U-shaped supporting bracket 11, the central portion of which is apertured at 11' to receive means for securing the unit either to the ceiling as shown or to some other fixed part of the building. Journalized near the free terminals of U-shaped bracket 11 is an axle 12 on which is rigidly secured a spool 13. Mounted on axle 12 between one terminus of spool 13 and bracket 11 is a conventional expansion type brake assembly 14 operated by a spring actuated brake lever 15 for stopping rotation of spool 13.

To control the speed of rotation of spool 13 and consequently the rate of descent of the escapee, the lowering unit is equipped with a governor 16 mounted on an extended portion of axle 12. Should the speed of rotation of spool 13 exceed a predetermined rate, the governor weights 17 operate to set brake 14. For re-winding spool 13 after each descent, axle 12 is provided with a crank 18.

Carrier unit B consists of a supporting backboard 19 to the upper part of which is secured a U-shaped bracket 20. Rotatably mounted between opposing sides of said bracket is a spool 21. Between one end of spool 21 and bracket 20 is a conventional expansion type brake assembly 22. The assembly includes a brake lever 23 operable to prevent rotation of spool 21; a tension spring 24 one end of which is secured to a bracket-supported thread-

edly adjustable rod 25, the other end of the spring being engaged to the brake lever 23; and a thumb-operated lever 26 mounted on supporting backboard 19 and acting through an intermediate arm 27 to work against spring 24 and set the brake (see Figure 4) at the option of an escapee.

The lower extremity of supporting backboard 19 is apertured at 28 and the lateral margins of said backboard are provided with ears 29 for hooking on safety belts 30 or any other suitable securing means which are fastened about the escapee.

Mounted at the top of the U-shaped bracket 20 and extending between the sides thereof is a strip 31 apertured at 32 for the egress of brake rope 33 which is wound about spool 21 and extends to brake lever 15 of the lowering unit. The topmost portion of backboard 19 is bent to form a flange 34 for the reception of a swivel eye 35 to which is secured load rope 36. The rope 36 extends upwardly to and is normally wound on spool 13 of the lowering unit. The swivel eye prevents skewing motion of the carrier unit.

In operation, the escapee releases brake 22 of the carrier unit by operation of thumb-lever 26. This in turn relieves the braking pressure exerted by brake rope 33 on brake lever 23 of the lowering unit permitting rotation of spool 13 under the weight of the escapee and consequent descent of the carrier unit. In case the speed of descent exceeds a predetermined rate, governor 16 serves to control the rotation of spool 13 and slow down the descent of the carrier unit.

If it is desired to stop the carrier at some point in its descent, thumb lever 26 is set to apply brake 22 thereby stopping rotation of spool 21. This causes brake rope 33 to draw taut and actuate brake lever 15, halting the descent of the carrier unit in an obvious manner.

Although I have herein shown and described a preferred embodiment of the present invention, such has been done for purposes of illustration, and I am aware that various changes may be made therein which come within the scope of the claim hereto appended.

What I claim is:

A fire escape comprising a carrier unit which includes a supporting backboard extending forwardly at its upper end to provide means for connection to the cable of a lowering unit, said lowering unit including a spool having a brake on one end and a lowering cable reeled on the spool, a U-shaped bracket mounted on the backboard with the legs thereof extending forwardly from the backboard, a second spool rotatably mounted in the U-shaped bracket, a brake band in surrounding relation to a brake drum at one end of the second spool, a lever actuating the brake band, a manual lever pivotally mounted on the backboard, a link connecting the two said levers, and a spring carried by one leg of the bracket and terminally connected with the first said lever to normally keep the brake band out of engagement with the drum, the second said lever being depressible against tension of the spring to actuate the brake band, and a second cable on the spool for operative connection with the brake of the lowering unit.
